DESIGN FOR AN HONOR ROLL PLAQUE

Philip G. Rosier, Chicago, Ill., assignor to Philip G. Rosier, George J. Spatuzza, and Frank E. Bourget, copartners, doing business under the firm name of National Plaque Specialties Co., Chicago, Ill.

Application December 23, 1942, Serial No. 109,112

Term of patent 3½ years

To all whom it may concern:

Be it known that I, Philip G. Rosier, a citizen of the United States, residing at Chicago, in the county of Cook and State of Illinois, have invented a new, original, and ornamental Design for an Honor Roll Plaque, of which the following is a specification, reference being had to the accompanying drawing, forming part thereof.

In the drawing Figure 1 illustrates in plan

view an honor roll plaque embodying the features of the invention.

Fig. 2 is a side view of the plaque.

The characteristic features of the design reside primarily in the headboard portion of the plaque.

I claim:

The ornamental design for an honor roll plaque, substantially as shown and described.

PHILIP G. ROSIER.
